EDWIN G. TEMPLETON, OF AKRON, OHIO, ASSIGNOR TO THE GOODYEAR TIRE & RUBBER COMPANY, OF AKRON, OHIO, A CORPORATION OF OHIO.

VULCANIZER FOR CORD TIRES.

1,317,669.

Specification of Letters Patent. Patented Sept. 30, 1919.

Application filed October 8, 1917. Serial No. 195,389.

To all whom it may concern:

Be it known that I, EDWIN G. TEMPLETON, a citizen of the United States, residing at Akron, in the county of Summit and State 5 of Ohio, have invented new and useful Improvements in Vulcanizers for Cord Tires, of which the following is a specification.

My present invention relates to vulcanizer presses and more particularly to the type 10 of steam heated vulcanizer press which is employed for the vulcanizing of tires.

In accordance with the present practice governing the use of tire-curing vulcanizer presses, or heaters, a chain and grapple is 15 employed to lift the heavy cover from its locked position at the mouth of the press, in order that the cured tires within the press may be successively raised upon the ram platen to the mouth of the press for removal 20 therefrom. When the molds are lowered into the press, the cover is lowered into place by means of a chain and grapple and locked in position over the press mouth. Inasmuch as this cover forms a fixed head against 25 which all of the molds are compressed by upward movement of the ram platen, it will be obvious that its durable construction necessitates great weight, with a consequent awkwardness and lack of ease in handling.

30 The vulcanization of some types of tires, notably those known as cord tires, requires relatively short curing periods and, since an economical operation of any press unit requires its reloading immediately upon the 35 discharge of any set of molds which has completed the period of vulcanization, it will be apparent that the laborer having charge of the press will be forced to handle the heavy heater cover very frequently during 40 the course of a working day.

It is the principal object of this invention, accordingly, to lighten the manual labor required in charging and discharging the tire vulcanizing press at frequent intervals, by providing means of a mechanical 45 nature which are adapted to undertake the removal and replacement of the heater cover without the necessity of manual supervision.

It is the more specific object of the invention to provide a cover lifting and supporting means to be carried directly by the ram platen and in such a manner that the lifting and supporting means for the cover will be inoperative thereupon when the cover 55 is locked in position over the press mouth,

but will become automatically effective to remove the cover from the mouth of the press well when it has been unlocked and is free for removal.

It is a further object of the invention to 60 provide a lifting and supporting apparatus for the press cover of the type set forth which is of such a nature that it may be added as extra equipment to any well known type of press already in use without requiring any alteration in press construction other than the addition thereof of the parts 65 composing the desired embodiment of this invention.

The above and other incidental objects 70 of a similar nature, which will be herein-after more specifically treated, may be accomplished by such means as are illustrated in the accompanying drawings, described in the following specification, and then 75 more particularly pointed out in the claims which are appended hereto and form a part of this application.

With reference to the drawings, wherein there has been illustrated a preferred embodiment of the invention as it is reduced to practise, and throughout the several views of which, similar reference numbers 80 designate corresponding parts:

Figure 1 is a view in combined side elevation and vertical section of an ordinary type of vulcanizer press and provided with the mechanical means of this invention; 85

Fig. 2 is a partial top plan of the press with the cover in unlocked position; 90

Fig. 3 is a detail vertical section showing the method in which the cover lifting and supporting means become operative on an unlocked cover;

Fig. 4 is a similar sectional view of the press with the cover locked thereon, and with the lifting and supporting means therefor, accordingly, ineffective to remove the cover; and 95

Fig. 5 is a diagrammatic view of a slightly 100 modified form of my invention.

There is illustrated in Fig. 1 a press generically denoted by the number 5 of any ordinary or usual construction. The mouth of this press is provided with an annular casting or metal fixture 6, whose inner rim is formed with a plurality of female locking lugs 7 which are equidistantly spaced from each other and which overlie the annular locking channel 8. The cover 9 of the press 105

fits relatively loosely within the annular casting 6 and is provided with male locking members 10 of substantially the same configuration as the female lugs 7 and equidistantly spaced in order that they may pass vertically through the spaces between the lugs 7 until reaching the interior of the locking channel 8, at which time they may be partially rotated to pass underneath the female lugs 7 and thus maintain the cover 9 in locked position over the well mouth. This castellated or breech lock mechanism is of the type customarily employed for tire vulcanizers owing to its simple and efficient operation.

It is upon the fact that the locking cover 9 of the press is given an angular rotational movement through a slight angle in order to move from its locked position to its unlocked position, or vice versa, over the press mouth, that the present invention is primarily based. Broadly, I contemplate the provision of rods secured to the platen of the ram and adapted to engage solidly with the cover when the latter is in its unlocked position, or to telescope through the cover when the latter is in its locked position, thus providing means for raising the cover in accordance with the upward movement of the ram when the cover has been rotated into the proper unlocked position, while the cover lifting and supporting rods will be ineffective to engage the cover when the latter has been rotated from its unlocked position into its locked placement.

Through the bottom of the press well 5 there extends a ram plunger 11 bearing at its upper extremity a platen 12 upon which the mold or molds 13 may be supported. The construction illustrated may be taken as typical of a hydraulic press, and to this ordinary construction there is added, by the present invention, a plurality of supporting webs 14, preferably three in number and each one extending laterally from the plunger 11 to similarly support the cover lifting and supporting rods 15. These rods are carried well toward the wall of the vulcanizer press 5 in order that they may form the least possible obstruction to the insertion of molds between the pairs of adjacent rods and on to the ram platen, or the removal of the molds therefrom. The upper extremities of the rods pass through guide sleeves 16 with which there is adapted to vertically register a boss 17 formed on the under surface of the cover 9. This boss is preferably provided with a recess 18 in which the upper end of the platen rods 15 may be seated when cover 9 is occupying its unlocked position with respect to the annular casting 6 at the well mouth, being that position which is illustrated in Fig. 1.

With the parts in position of Fig. 1, (wherein the cover is in unlocked position),

it will be apparent that upward movement of the platen 12 will force all three of the cover lifting rods 15 into engagement with the recesses of their respective bosses 17 on the cover and will lift the cover from its engagement with the annular casting 6 and support it thereabove during any loading or unloading process for the press. At the conclusion of this loading or unloading process, retraction of the plunger 11 into a ram pot (not shown) will restore the cover 9 correctly to the position shown in this figure, requiring but a slight rotation of the cover to engage its locking lugs 10 with the fixed lugs 7 of the annular casting 6 at the well mouth.

This partial rotation of the cover into its locked position brings a telescoping tube 19 directly into vertical registry with each of the cover supporting rods 15. These tubes 19 are set into the top of the cover in some such manner as is illustrated in Fig. 4 and are set just such a horizontal distance from the vertical axis of the bosses 17 as will permit the tubes to move over into registry with the reciprocating cover lifting rods or bars 15 when the cover is locked into the well mouth.

Upward movement of the ram plunger 11, with the cover in its locked placement, serves to compress the mold parts 13 against the locked cover 9, the rods 15 being ineffective to engage the cover since they have the telescoping movement within the tubes 19 shown in Fig. 4. It will be apparent that provision of three of the rods 15, which will be ample to raise and support the cover 9, will not interfere materially with the loading of the molds 13 upon the ram plunger or the unloading of the molds therefrom.

In Fig. 5 I have illustrated a slightly modified form wherein I employ four supporting rods 15 for a heavier cover suitable for a larger vulcanizing press to accommodate molds of a larger diameter than can be inserted in the vulcanizing press previously described.

What I claimed is:

1. A combination with a tire vulcanizer, provided with a plunger reciprocable within the body of the vulcanizer and a cover having a removable locking engagement over the mouth of the vulcanizer, said cover being oscillatable through slight arcs between its locked and unlocked positions, of cover lifting and supporting means carried by said plunger and having a fixed path of reciprocation in accordance with the movement of said plunger, a rod engaging boss and a telescoping tube carried by the cover as an adjunct of the lifting and supporting means, said boss being rotated into registry with said lifting and supporting means when the cover is moved from its locked to its unlocked position, and said tube being moved

registry with said lifting and supporting means when the cover is rotated from its unlocked to its locked position.

2. The combination with a vulcanizing press provided with a plunger, of a cover provided with openings therein and tubes arranged at said openings, bosses on the under side of said cover, rods stationarily mounted on the plunger, said bosses being in registry with said lifting rods when the cover occupies its unlocked position, and said tubes being in registry with said lifting rods when the cover occupies its locked position.

3. The combination with a vulcanizing press provided with a plunger, of a cover provided with openings, rods stationarily mounted on the plunger, bosses on the under side of said cover, said bosses adapted to be engaged by the free ends of said rods when the cover occupies its unlocked position, and tubes at the openings in the cover, into which the free end portions of the lifting rods can

project when the cover occupies its locked position.

4. The combination with a vulcanizing press provided with a plunger, of a cover provided with openings, lifting rods stationarily mounted on the plunger, guides through which the free end portions of said lifting rods pass, bosses on the under side of said cover, said bosses provided with recesses into which the free ends of the lifting rods are adapted to fit when the cover occupies its unlocked position, and tubes at said openings, into which the free end portions of the lifting rods can project when the cover occupies its locked position.

In testimony whereof, I have signed my name in the presence of two subscribing witnesses.

EDWIN G. TEMPLETON.
